REACTION TYPE SPRINKLER

Vincent Chavez, Los Angeles, Calif.

Application August 11, 1955, Serial No. 527,831

1 Claim. (Cl. 299—69)

This invention relates to a sprinkler for lawns or the like.

An object of this invention is to provide an improved sprinkler of the rotating type, wherein the rotation is produced by means of a jerking or partial movement of the sprinkler nozzles.

Another object of this invention is to provide an improved sprinkler wherein the speed of rotation may be adjusted in accordance with the pressure and flow of water from the nozzles.

A further object of this invention is to provide a sprinkler wherein the sprinkler head and operator are loosely assembled together without the aid of springs and the rotating action is produced when the jet of one of the nozzles is in action.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawing:

Figure 1 is a detail side elevation of a sprinkler constructed according to an embodiment of this invention.

Fig. 2 is an end elevation of the sprinkler.

Fig. 3 is an end elevation of the sprinkler opposite to that shown in Fig. 2.

Fig. 4 is a detail elevation of the impeller or operator for the sprinkler head.

Fig. 5 is a plan view of the device showing the impeller in operative position relative to the sprinkler head.

Fig. 6 is a plan view partly in section showing the impeller in initial starting position.

Fig. 7 is a fragmental vertical section of the device.

Referring to the drawings, the numeral 10 designates generally a sprinkler head which is formed of a lower pipe section 11 adapted to be threaded onto a supply pipe 13. The pipe section 11 is formed with a central bore and the stem 12 of the sprinkler head is loosely or rotatably disposed in the connection 11. The stem 12 is provided at its lower end with an annular flange or nut 14, whereby the stem 12 will be held against undue upward movement relative to the fitting 11. The head 10 includes a pair of upwardly and outwardly directed tubular arms 15 and 16 connected to a crank 17 extending from the upper end of the stem 12. The arm 15 has mounted in the upper outer end thereof a nozzle 18, and the arm 16 has mounted in the upper end thereof a nozzle 19. These nozzles 18 and 19 are of like construction and are adapted to produce a stream of water which is relatively solid as it leaves the ends of the nozzles 18 and 19.

A vertically disposed shaft 20 is fixedly secured in the connecting wall 21 between the arms 15 and 16 and the shaft 20 has mounted on the upper end thereof a nut

2

22. A cup-shaped impeller generally indicated at 23, is disposed outwardly from the nozzle 18 and the impeller 23 is formed of a vertical bar 24, upper and lower walls 25 and 26 respectively, and an outer arcuate connecting wall 27. The inner surface of the impeller 26 where the outer wall 27 joins with the vertical wall 24 is formed on a concave, as indicated at 28.

The inner end of the wall 24 is provided with a cut-out as indicated at 29, so that the wall 24 may partly project over the outer end of nozzle 18. The impeller 23 is carried by an elongated lever arm 30 secured to a central bushing 31 rotatably mounted on the vertical shaft 20. The impeller with arm 30 is balanced by means of an oppositely extending and upwardly curved balancing lever arm 32 extending from the bushing 31. The arm 32 is disposed in a position out of contact with a water stream being ejected from nozzle 19. In order to provide a means whereby sprinkler head 10 will be progressively rotated about the fitting 11, I have provided a hammer or impact member 33, which is disposed at right angles to a threaded bore 34 extending through lever arm 30.

Bolt 34 is adjusted relative to the arm 30 by threading the latter through arm 30 and locking the bolt 30 by means of a lock nut 35. The bushing 31 is loosely disposed on vertical shaft 20 and may have vertical movement thereon simultaneously with rotary movement. Vertical movement of fitting 11 produces vertical movement of impeller 23 which is produced by means of cam roller 36 secured to shaft 20 by means of a set screw 37. The bushing 31 is provided at the lower end thereof with an annular collar 38 and a cam engaging pin 39 extends from the collar 36 and rides on the inclined cam surface 40 of cam 36.

In the use and operation of this sprinkler the fitting 11 is secured to a supply pipe 13 with the fitting 11 in a vertical position. When water is forced upwardly and outwardly from the nozzles 18 and 19, this water will be disposed adjacent the nozzles in a relatively solid stream. The water passing out of nozzle 18 will strike impeller member 23 and thereby cause impeller member 23 to partially rotate relative to nozzle head 10. When impeller 23 moves upwardly as shown in Figs. 5 and 6, which in the actual operation of the device is counter-clockwise, the hammer or impact member 23 will strike nozzle 18 and the weight of the impeller 23 with arm 30 and arm 32 will produce a jerking rotary movement of impeller head 10 in a counter-clockwise direction. An impeller 23 moves to the left away from the stream passing through nozzle 18, impeller 23 with arm 30 and fitting 31 will rise upwardly by riding of cam pin 39 on cam surface 40.

When impeller 23 is disposed out of contact with the water stream or nozzle 18 the weight of the impeller structure including impeller 23 with arms 30 and 32 and bushing 31, will gravitantly rotate impeller 23 clockwise toward the water stream. This will bring the impeller 23 back into engagement with the water stream and the result will be a reciprocation back and forth of impeller 23 and at the same time the impact of hammer 33 will produce gradual rotation of the sprinkler head 10. This jerking movement of the sprinkler head will have the effect of distributing the water stream from nozzle 18 over a relatively wide area as the sprinkler head rotates. This is produced by the partial cutting off of the stream from nozzle 18 and the force of impact of hammer 33, which will produce a spreading or breaking of the two streams from nozzles 18 and 19.

What is claimed is:

A lawn sprinkler comprising a stationary member for connection to a water supply, a sprinkler head loosely and rotatably carried by said member, said head comprising a vertical tubular stem, a pair of divergent tubu-

lar arms extending from said stem, a nozzle on the outer end of each arm, a vertical shaft extending upwardly from the junction of said arms, a lever pivotally carried by said shaft, an impeller blade carried by said lever and disposed in a position to at least partly intersect the stream of water from one of said nozzles, an impact member carried by said lever engageable with one of said nozzles to thereby progressively rotate said head, upon movement of said impeller relative to said head, a cam fixed on said shaft having a cam surface inclined to the vertical, and a cam engaging pin carried by said lever adapted upon rotation of said lever to raise said impeller out of contact with said stream.
